UNITED STATES PATENT OFFICE.

JOHN F. O'CONNOR OF CHICAGO, ILLINOIS, ASSIGNOR TO WILLIAM H. MINER, OF CHAZY, NEW YORK.

VERTICALLY-ADJUSTABLE SIDE BEARING.

1,257,920.

Specification of Letters Patent. Patented Feb. 26, 1918.

Application filed June 9, 1917. Serial No. 173,849.

To all whom it may concern:

Be it known that I, JOHN F. O'CONNOR, a citizen of the United States, residing at Chicago, in the county of Cook and State 5 of Illinois, have invented a certain new and useful Improvement in Vertically-Adjustable Side Bearings, of which the following is a full, clear, concise, and exact description, reference being had to the accompanying drawings, forming a part of this specification.

This invention relates to improvement in vertically adjustable side bearings.

One object of the invention is to provide 15 a side bearing more particularly adapted for use on railway cars and wherein are employed anti-friction elements such as rockers in combination with means to change or adjust the effective height of the bearing to 20 compensate for different operating conditions.

Another object of the invention is to provide a side bearing of the character above described wherein the adjustment can be 25 effected without disturbing the relation of the anti-friction elements and the members immediately associated therewith.

In the drawing forming a part of this specification, Figure 1 is a vertical longitudinal sectional view of a side bearing showing the same in position between the body and truck bolsters of a car. And Figs. 2 and 3 are transverse vertical sectional views, taken on the lines 2-2 and 3-3, respectively, of Fig. 1.

In said drawing, 10 denotes the upper portion of a truck bolster to which the improved side bearing is preferably attached, and 11 indicates the under portion of a body bolster, 40 the bolsters being movable in a well known manner.

The improved side bearing, as shown, comprises a base casting A, a pair of anti-friction rockers B-B, a bearing cap C, a bearing plate D, and spring E for returning the parts to normal position.

The base casting A comprises a lower wall 12 riveted to the truck bolster; a central upwardly extending rib or flange 13 having 50 an elongated horizontally extending slot 14; and side walls 15-15 at opposite sides of the central enlargement 16 from which the flange 13 extends. The upper surface of the lower wall 12, as will be understood, 55 forms bearing surfaces for the under sides

17 of the rockers B and to maintain the rockers in proper position at all times, the rockers are provided with recesses 18 on their under faces with which coöperate teeth 19 formed on the base casting. The 60 upper faces of the rockers B are provided with curved bearings, as indicated at 20, which bearings are concentric with the lower faces 17 of the rockers and are adapted to coöperate with correspondingly convexly 65 curved bearings 21-21 formed integrally with the cap plate C. The bearings 21 of the cap plates are formed in pairs, two for each rocker B, as clearly indicated in Fig. 3, and separated by a recess 22 to provide 70 the necessary clearance when the cap plate moves longitudinally over the vertically extending flange 13 of the base casting. Each of the bearings 21 of the cap plate is also made hollow, as indicated at 23, so as to 75 accommodate oil and waste, indicated at 24, to facilitate oiling of the bearing. The waste 24 may be inserted through openings 25 and the oil is adapted to feed to the rocker bearing surfaces through perforations 26. 80

The cap plate C is provided on each side thereof with a series of longitudinally extending ribs 27 with which coöperate corresponding series of longitudinally extending ribs 28 formed on the inner faces of the depending side walls 29-29 of the upper bearing plate D. As will be obvious, by engaging the ribs 27 and 28 in different positions, the height of the bearing plate D can be varied and without disturbing the relation 90 of the rockers B with the base casting and cap plate. To retain the bearing plate D and cap plate C in any adjusted position, bolts 30 are employed, located as indicated most clearly in Fig. 1, said bolts being held 95 by nuts 31.

To return the parts to normal position after each actuation, the spring E, which is mounted within the slot 14, has transversely extending spring followers 32-32 at its ends 100 which followers bear against the ends of the slot in the flange 13 and said followers are also extended into suitable slots 33 in the depending side walls of the cap plate C, as clearly illustrated in Fig. 2. Hence, 105 when the two bolsters move relatively to each other and pressure is brought to bear on the bearing plate D, it is obvious that the plates D and C will be shifted longitudinally and the rockers B oscillated. This movement 110

causes one of the followers 32 to move toward the opposite follower and compress the spring E. Upon removal of the pressure on the bearing, the spring E expands and 5 forces the followers 32 apart to their normal position, which thereby returns the rockers and plates C and D to normal position.

Each of the rockers B is also centrally recessed, as indicated at 35, to clear the central 10 vertical web 13 in the rocking movements. 10 Each of the spring followers 32 is provided with a cup 36 in which are seated the ends of the spring E to prevent the latter from becoming displaced.

15 I claim:

1. In an anti-friction bearing, the combination with a retaining member, of an anti-friction element carried thereby and having a bearing thereon, a cap plate 20 operable with said anti-friction element and also having bearing on said element, means for locking said cap plate and member together to prevent accidental separation but at the same time permitting relatively longitudinal movement, and a bearing plate 25 adjustably mounted on said cap plate.

2. In an anti-friction bearing, the combination with a retaining member, of a rocker mounted on said member, a cap plate mounted 30 on the rocker, means for locking said cap plate and member so as to prevent accidental vertical separation but permitting relatively longitudinal movement, and a bearing plate adjustable with respect to 35 said cap plate.

3. In an anti-friction bearing, the combination with a retaining member, of a plurality of anti-friction elements carried by 40 said retaining member and having bearing thereon, a cap plate engaging said anti-friction elements, means for locking said cap plate to said retaining member so as to prevent accidental vertical separation but permitting relatively longitudinal movement, and a bearing plate 45 adjustably mounted on said cap plate.

4. In an anti-friction bearing, the combination with a retaining member, of a plurality of rockers mounted on said retaining 50 member, a cap plate supported on said rockers, means for locking said cap plate to the retaining member to prevent accidental separation but permitting relatively longitudinal movement, and a bearing plate adjustably mounted on said cap plate.

5. In an anti-friction bearing, the combination with a retaining member, of a plurality of anti-friction elements carried by 55 said retaining member and having bearing thereon, a cap plate engaging said anti-friction elements, means for locking said cap

plate to said retaining member so as to prevent accidental vertical separation but permitting relatively longitudinal movement, a bearing plate adjustably mounted on said 65 cap plate, and spring means for returning said elements, cap plate and bearing plate, to normal position after each actuation of the bearing.

6. In an anti-friction bearing, the combination with a retaining member, of a plurality of rockers mounted on the retaining member, a cap plate mounted on the rockers, and means for both locking said cap plate to the retaining member to prevent 70 vertical separation thereof and at the same time adapt it to return said cap plate to normal position after each actuation of the side bearing.

7. In an anti-friction bearing, the combination with a retaining member, of a plurality of rockers mounted on the retaining member, a cap plate mounted on the rockers, means for both locking said cap plate to the retaining member to prevent vertical 85 separation thereof and at the same time adapt it to return said cap plate to normal position after each actuation of the side bearing, and a bearing plate vertically adjustable 90 with respect to said cap plate.

8. In an anti-friction bearing, the combination with a retaining member and a parallel cap plate, of a plurality of rockers interposed between said cap plate and retaining member, said cap plate being provided with recesses in communication with the bearings on the rockers, said recesses being adapted to hold waste and oil. 95

9. In an anti-friction bearing, the combination with a base casting, of a pair of rockers mounted on said base casting, a cap plate mounted on the rockers, spring means and followers therefor located between the rockers and adapted to lock the cap plate and base casting from accidental vertical separation while permitting relatively longitudinal movement, and a bearing plate 100 adjustably mounted on said cap plate. 105

10. In an anti-friction bearing, the combination with a retaining member, a cap 110 plate, and a bearing plate all arranged in parallel, of a plurality of anti-friction elements interposed between said cap plate and said retaining plate, and integral co-operating means formed on said bearing 115 plate and cap plate adapted to permit adjustment therebetween.

In witness that I claim the foregoing I have hereunto subscribed my name this 21st day of May, 1917.

JOHN F. O'CONNOR.
